UNITED STATES PATENT OFFICE

169,934

GARMENT HANGER

Herbert Coon, Great Neck, N. Y., assignor to Red Wing Products, Bellerose, N. Y., a partnership

Application June 19, 1952, Serial No. 20,276

Term of patent 14 years

(Cl. D80—8)

To all whom it may concern:

Be it known that I, Herbert Coon, a citizen of the United States, residing at Great Neck, county of Nassau, and State of New York, have invented a new, original, and ornamental Design for a Garment Hanger, of which the following is a specification, reference being had to the accompanying drawing, forming a part thereof.

The figure is a perspective view of a garment hanger, showing my new design.

I claim:

The ornamental design for a garment hanger, substantially as shown.

HERBERT COON.
